JAMES L. ARTHUR, OF ANDERSON, INDIANA, ASSIGNEE TO DELCO-REMY CORPORATION, OF DAYTON, OHIO, A CORPORATION OF DELAWARE

IGNITION APPARATUS

Application filed June 13, 1927. Serial No. 198,682.

This invention relates to ignition apparatus for internal combustion engines, and more particularly to ignition apparatus for automobiles in which a storage battery is used to supply current for the engine starting motor and also for the ignition apparatus.

One of the objects of the present invention is to obtain sufficient energy from the ignition coil for satisfactory ignition during the cranking of the engine, although the voltage impressed by the battery at the terminals of the primary ignition circuit may be below normal. In this invention, this object is accomplished by providing an ignition coil having two sets of primary windings which are connected in multiple with the battery during the cranking operation and in series with the battery during the normal running of the engine. When the primary windings are connected in parallel the ignition coil will be energized to the same extent at one-half battery voltage as when the coil windings are connected in series with a battery at normal voltage. This ignition system therefore provides satisfactory ignition during engine cranking although the battery may be partly discharged and considerably below normal voltage, especially when required also to supply current to an electric starting device.

Another object of the present invention is to wind the primary of an ignition coil in such a way as to provide for making connections at one end of the coil with a switch for changing the connections of the primary windings from parallel to series.

Further objects and advantages of the present invention will be apparent from the following description, reference being had to the accompanying drawings, wherein a preferred form of embodiment of the present invention is clearly shown.

In the drawings:

Fig. 1 is a wiring diagram of an ignition system embodying the present invention.

Figs. 2 and 3 are diagrammatic views showing other positions of a switch included in the diagram of Fig. 1.

Fig. 4 is a longitudinal sectional view of a unit including the coil and switch shown diagrammatically in the other views.

Referring to Fig. 4, 20 designates the center core of an ignition coil, and the core is surrounded by a secondary winding 21 wound upon a non-conducting tube 22. Around the secondary 21 there is wound a primary coil 23 comprising four layers 24, 25, 26 and 27, 24 being the innermost and 27 the outermost. In the wiring diagram, the core 20 is shown in five different places in order that the coils 21, 24, 25, 26 and 27 may be shown separately. 55 The start turn of the coil 24 is connected with the outside turn of the secondary coil 21 as indicated by the dot 30 and both of these turns are connected together with a switch contact 31. The inside turn of the secondary coil 21 is grounded to core 20 which is connected by a lead 32 with the center contact 33 of a distributor head 34 having a circular row of terminals 35 connected with engine spark plugs 36. A rotor 37 cooperates with center contact 33 to distribute sparking impulses to the various terminals 35. The outside lead 40 of the coil 27 is connected with a switch contact 41 and also by wire 42 with a terminal 43 which is connected with an ignition timer 44 grounded at 45. The switch contact 31 is connected by wire 46 with a terminal 47 which may be connected with a battery 48 grounded at 49.

In the usual operation of winding the core layers of primary coils the end lead of the coil layer 25 would be joined with a start lead of the coil layer 26 by a wire turn indicated in Fig. 1 by a dot and dash line 50. This wire turn is severed in order to form portions 50a and 50b which are connected respectively with switch contacts 51 and 52. The stationary contacts of the switch operate with movable contacts 53 and 54 which are carried by a non-conducting carrier 55 which may be rotated by any suitable operating handle which will be described later in connection with Fig. 4. 85

A reverse current relay 60 connects a battery-charging, engine-driven generator 61 grounded at 62 with the battery 48 when the generator attains a certain voltage and disconnects the battery from the generator when the voltage of the latter falls below a certain value. 95 100

When the switch contacts are in "off" position as shown in Fig. 2, the ignition coil will be disconnected from the battery. During the starting of the engine the switch contacts 53 and 54 are moved into "start" position shown in Fig. 1 in order to contact in parallel with the battery 48, the primary winding comprising coils 24 and 25 and the primary winding comprising coils 26 and 27. In Fig. 1, the arrows 70 which are used to indicate the direction of current from the battery clearly indicate these parallel circuits, the junction points of which are at contacts 31 and 41. This connection will reduce the resistance of the primary circuit so that the total ampere turns in the primary circuit will be as much with a battery at half voltage, as would be available from a battery at full voltage if the battery is connected with the primary windings in series. Thus sufficient coil energy for satisfactory ignition may be obtained from a partially discharged battery.

After the engine has become self-operative and it has attained a speed sufficient to operate its battery charging generator 61 at normal voltage, the switch contacts 53 and 54 may be moved into the "run" position shown in Fig. 3 in which contact 54 is out of engagement with the stationary contact and the contact 53 bridges the contacts 51 and 52. This circuit change will cause all of the primary windings to be connected in series so as to increase the resistance of the primary ignition circuit when normal voltage of the generator 61 is impressed upon it. When this connection is made current will flow through the battery 48 in the direction of arrow 70 into contact 31 and thence through the coil layers 24 and 25 to the contact 51 as indicated by the arrow 70. From contact 51 current flows through contact 53 to the contact 52 and thence through wire 50b to the coil layers 26 and 27 to the contact 41 as indicated by the arrow 70. It will be noted that current flows in the same direction through the coil layers 24 to 27 inclusive regardless of whether the switch is in the "start" or "run" position. Thus the effect of the coil is always cumulative regardless whether they are connected in parallel or in series.

The present invention provides further for the bringing out of all the coil leads 39, 50a, 50b and 40 at one end of the coil assembly so that they may all be conveniently connected with a switch located at one end of the coil. This construction permits the advantageous use of an ignition coil and switch unit as an embodiment of the present invention. This unit will now be described with reference to Fig. 4. The central core 20 extends into recesses provided by non-conducting bodies 80 and 81 which are attached to a tubular metal case 82 and cooperate therewith to provide an enclosure for the coil assembly and also an external magnetic circuit provided by a

plurality of turns of sheet iron 83 separated by paper insulation 84. The member 81 is attached to a sheet metal cover 85 and carries a cable-receiving sleeve 86 extending through a central hole in the cover 85 and provided internally with a metal lining 87 which provides the high tension terminal 32 shown in the diagram. The metal lining 87 is connected by a pin 88 with the core 20 upon which the inside turn of the secondary 21 is grounded. The body 81 and the cover 85 also support the terminals 47 and 43 shown diagrammatically in Fig. 1. The cover 85 is joined to the case 82 by spinning its flange 89 around a flange 90 of the case 82.

The body 80 is attached to the case 82 by spinning into the case two annular grooves 91 and 92 which provide on the inside of the case annular ridges 91a and 92a between which the body 80 is clamped. The case 82 also has an extension 93 for receiving a cylindrical switch frame 94 which is held in position against the body 80 by spinning the edge 95 of the case 82 against a shoulder 96 provided by the frame 94. The frame 94 supports a key shaft 97 to which is attached the non-conducting contact carrier 55 carrying the contacts 53 and 54. The body 80 carries stationary contacts 31, 41, 51 and 52, the contacts 41 and 52 being shown structurally in Fig. 4. These contacts are tubular and receive the wires leading from the primary coil layers. The wires 42 and 46 leading from the contacts 31 and 41 respectively to the terminals 43 and 47 respectively may be encased within non-conducting fabric sleeves extending lengthwise of the case 82. One of the sleeves is designated by numeral 100 in Fig. 4. Actually the case 82 need not be bulged as shown in Fig. 4 to accommodate the sleeve 100; this bulge is shown for sake of convenience to provide room for showing the sleeve 100 which, in practice, would be flattened between the primary winding 23 and the external magnet iron 83.

The key shaft 97 may be turned only by the use of the proper key 98 cooperating with bars 99 to withdraw all of them from grooves 101 provided by the switch frame 94.

It is therefore apparent from the foregoing description, my invention and mode of operation that I have provided an ignition system for obtaining satisfactory ignition for engine starting from a storage battery or other current source which may be below normal voltage; and I have also provided a unitary coil and lock switch structure embodying the features of my ignition system and so constructed and arranged that it may be connected with a current source, ignition timer and ignition distributor in the same manner in which the conventional ignition coil is connected with these instruments.

While the form of embodiment of the present invention as herein disclosed, constitutes

a preferred form, it is to be understood that other forms might be adopted, all coming within the scope of the claims which follow.

What is claimed is as follows:

- 5 1. An ignition coil comprising in combination, a casing, a coil assembly having a secondary winding, a plurality of primary windings wound serially upon said secondary, the starting and ending convolutions of the primary winding all terminating adjacent one end of the casing, a switch providing a cover for the casing and electrically inserted between the primary windings, a partition member disposed between the switch and windings and providing terminals for the windings accessible to the switch, said switch being adapted to open and close circuits through said ignition coil, and to couple the primary windings either in series
10 or in parallel relation.
- 15 2. A unitary structure providing an easy starting ignition coil for explosive engines, comprising in combination, a plurality of windings inductively related, one of said windings being electrically divisible into parts, means rigidly supporting said windings and providing terminals for each part thereof, a casing enclosing said windings and supporting means, and providing a chamber
20 within which one of said supporting means is disposed and the terminals of said divisible winding are accessible, a lock controlled movable contact with supporting frame closing off said chamber, said movable contact
25 disposed for cooperation with said accessible terminals, and means whereby the relation of said winding parts may be altered for starting and running ignitions.

In testimony whereof I hereto affix my signature.

JAMES L. ARTHUR.
